REFRIGERATING APPARATUS

Mahlon W. Kenney, River Forest, Ill., assignor to
General Household Utilities Company, Chicago,
Ill., a corporation of Delaware

Application April 18, 1936, Serial No. 75,032

13 Claims. (Cl. 62—126)

My invention relates in general to the art of refrigeration, and more particularly to refrigeration accomplished by means of the so-called compression evaporation cycle, wherein a suitable fluid refrigerating medium is cyclically compressed in gaseous form, condensed to liquid form, and finally evaporated for the purpose of absorbing heat, the invention having particular reference to the provision of an improved evaporator for use in such a system. The present application comprises a continuation in part of my co-pending joint application with Arthur R. Constantine, Serial Number 734,076, for Refrigerating system.

15 An important object of the invention is to provide, in a refrigerant evaporator adapted to contain an evaporable liquid refrigerant therein and having a header chamber, a device for ejecting non-evaporable liquid from said evaporator comprising a receiver above the liquid level in the header in position to catch liquid spattered above the said liquid level by violent ebullition, whereby the non-evaporable liquid may be drained from the receiver and out of the evaporator; a further 20 object being to form and arrange the evaporator to promote spattering ebullition in the evaporator near said receiver.

Another object is to form the evaporator with a gas exhaust outlet therein above the liquid level 30 and to provide means for draining said receiver to said outlet; a further object being to arrange the evaporator with a pair of headers and to mount the gas outlet in the header containing the receiver.

35 Another object is to interconnect the headers by means of a conduit opening at its opposite ends above the liquid refrigerant level in said headers.

A further object of the invention is to form the evaporator, in an inexpensive manner, by fastening together a pair of interfitting plates having 40 depressed portions forming refrigerant headers and ducts between the plates, when fitted together.

45 A further object is to emboss at least one of the evaporator forming sheets with a groove or grooves interconnecting said ducts intermediate the headers, and to form said grooves in position such that when the evaporator forming sheets are bent to form spaced apart walls containing 50 the headers, said grooves will provide registering inwardly extending heads on the facing surfaces of said spaced walls and adapted to provide means for supporting objects to be cooled between said spaced walls.

55 A further object is to provide one of the bead

forming grooves with a refrigerant inlet connection; a further object being to arrange the inlet connection to deliver liquid to a localized portion or portions of said bead opposite certain of the header connected ducts to promote vigorous ebullition therein. 5

These and numerous other objects and inherent advantages and functions of the invention will be apparent as the invention is more fully understood from the following description, which, 10 taken in connection with the accompanying drawings, discloses a preferred embodiment of my invention.

Referring to the drawings:

Figure 1 is a perspective view of refrigerating 15 apparatus embodying my present invention as assembled in a cabinet to form a domestic refrigerator;

Figure 2 is a sectional view in horizontal section taken through the device shown in Figure 1; 20

Figure 3 is a diagrammatic sketch showing electrical connections forming a system for powering and controlling the operation of the refrigerating apparatus shown in Figure 1;

Figure 4 is a top plan view, partially in section, 25 of a refrigerant evaporator forming a part of the apparatus shown in Figure 1;

Figure 5 is an end view of the evaporator shown in Figure 4;

Figure 6 is a sectional view taken substantially 30 along the line 6—6 in Figure 5; and

Figure 7 is a sectional view through a float controlled expansion valve forming a part of the apparatus shown in Figure 1.

To illustrate my invention, I have shown in 35 the drawings a refrigerating system comprising a compressor 11, a condenser 13 and an evaporator 15 connected together by suitable conduit means, including conduits 21 and 23 respectively, connecting the evaporator to form a refrigerant circulating system with the compressor and with the condenser. The circulating system provides means in which a refrigerating medium, in gaseous condition, may be drawn from the evaporator into and compressed in the compressor, and delivered thence to the condenser in which the compressed gaseous refrigerating medium may be liquefied as by cooling. The liquid refrigerant may be delivered from the condenser to the evaporator, preferably through an expansion device 40 comprising, in the illustrated embodiment, a float controlled valve 17. The liquid refrigerant thus delivered in the evaporator at relatively low pressure boils and changes its state from liquid to 45 gaseous condition with consequent absorption of 50 55

heat at the evaporator. The gaseous refrigerant thus evolved in the evaporator may be returned to the compressor for a repetition of the cycle. I find that it is desirable, though by no means 5 essential, to connect a dehydrator 19, of any suitable or preferred character, in the circulating system preferably between the condenser and the float controlled valve 17 for the purpose of removing, from the liquid refrigerant, any traces 10 of moisture contained therein, and thus prevent the possibility of ice accumulation through freezing of the moisture in any of the conduits forming the circulating system.

The float valve 17 is of simple construction 15 comprising a cylindrical sheet metal shell 16 forming side walls and an integral top, and a sheet metal cover portion 18 of generally semi-spherical configuration sealed to the lower opening of the cylindrical member 16 in order to form 20 a sealed housing providing a float chamber, the cup-shaped member 18 having peripheral flanges 22 sealed to the edges of the open ends of the shell 16. At its upper end, the shell carries an inlet fitting comprising a nipple 24 sealed in an 25 opening formed in the shell, the inner end of the nipple opening into the shell and carrying a filter element 26 preferably in the form of a wire screen. The outer end of the nipple 24 is threaded for connection with the conduit leading from 30 the condenser, so that condensed liquid refrigerants may be delivered through the nipple and screen into the float chamber. The cup-shaped portion 18 is shaped to receive a preferably spherical float member 28 carrying a valve stem 32 in position to enter a channelled sleeve 34 which is sealed at one end in an opening located 35 centrally in the bottom of the cup-shaped element 18, said element 18 having a strengthening ridge embossed therein around said opening. The channelled sleeve 34 provides a valve seat with 40 which the valve stem 32 cooperates to provide a control for the liquid refrigerant delivered from the float chamber through the channelled sleeve 34. The outer end of the sleeve 34 is provided 45 for connecting with the conduit leading to the evaporator inlet. The cup-shaped portion 18 is also embossed outwardly as at 38 to facilitate the connection of supporting legs 142 by which the casing forming the float chamber may be supported 50 in operative position. As the level of liquid rises in the float chamber, the float 28 will be raised and will lift the valve stem in the sleeve 34 to permit liquid refrigerant to escape from the float chamber to the evaporator. The walls of the 55 casing 16 are provided with an annular inwardly extending groove to interfittingly receive and support a corresponding grooved annular element 46 located within the float chamber in position to engage and limit the upward movement of the 60 float 28 therein, and thus prevent the possibility of the float rising to a height in the chamber permitting the valve stem 32 to escape from the sleeve 34.

I also find it convenient to provide the valve 65 chamber with means permitting the introduction of the refrigerating medium into the system at this point. To this end the upper portions of the casing 16 are formed with a channelled fitting 48 sealed in an opening in the casing with its 70 channel opening at one end into the float chamber. The fitting 48 outwardly of the float chamber is externally threaded to receive a cap 54 for sealing the outer end of the channel. The outer end of the channel is internally threaded to receive a valve 56, and the channel is formed with 75

a valve seat inwardly of the threaded portion adapted to be hermetically closed by screwing the valve 56 firmly against the seat. The valve 56 is provided with a channel which, when the valve 56 is raised from its seat, provides communication 5 between the outer and inner ends of the fitting, but which is so arranged that communication between the outer and inner ends of the fitting is cut off when the valve is firmly seated.

The system may be loaded with the refrigerating medium by removing the cap 54 and valve element 56 entirely from the fitting 48. A refrigerant delivery line is then connected to the fitting 48 as by threading it upon the threads which ultimately carry the closure cap 54. A desired 10 amount of refrigerant is then pumped into the system under pressure, the compressor being operated during the loading process in order to distribute the refrigerant properly in the system. After loading is completed, the refrigerant delivery connection is broken, the valve element 56 is inserted, but is not immediately seated. A 15 vacuum connection is then applied as by threading the same upon the threads normally carrying the cover cap 54. This vacuum connection 20 preferably has means manually operable without removing the connection in order to seat the valve. The vacuum connection is maintained for a sufficient interval to withdraw from the system all air and moisture which has entered 25 during the loading operation, the compressor during this air and moisture evacuation process, being preferably blanketed so that the system operates at a higher temperature than would otherwise be the case, thus driving off any air and 30 moisture which may be dissolved or occluded in the lubricant and refrigerant. Since the lubricant is in liquid condition when it reaches the float chamber, air and moisture will be drawn off through the fitting 48 and the vacuum connection 35 without abstracting any material quantity of the refrigerant.

Although the present invention is not necessarily restricted to a system embodied in domestic refrigeration, I have shown a refrigerating 40 system arranged in a cabinet 50 of any suitable or preferred construction affording a refrigerating compartment 58, in which the evaporator or heat absorber 15 is located. The compartment 58 preferably has heat insulating walls, and includes a 45 frontal opening giving access to the compartment, a door or other closure member 60 being provided for said opening. The motor compressor unit, the condenser, and condenser cooling means, and auxiliary apparatus for operating and controlling 50 the same, need not necessarily be housed in the cabinet at all, but may be separately enclosed or located remotely from the cabinet, if desired.

I prefer, however, to provide the cabinet with a mechanism compartment 62 adjacent and preferably immediately beneath the refrigerating compartment, and to house therein the compressor, condenser, and associated operating and control mechanism. The compressor, condenser, and associated operating and control mechanism which is enclosed in the mechanism housing, are preferably all mounted on a common panel 64 adapted for removable insertion in the cabinet so that the devices mounted on the panel may be assembled as a unit in the mechanism compartment. The 60 mechanism compartment also is preferably formed with a partition 66 defining chambers 68 and 72 on opposite sides of the partition, and within the walls of the mechanism compartment. The apparatus carried by the support 64 when 75

the same is assembled in the mechanism compartment, is located within the chamber 72 with the condenser 13 disposed in an opening 74 formed in the partition. The chamber 72 has an opening 16 through which air, blown into the chamber through the condenser and the opening 74 by the blower 27, may escape from the cabinet. The opening 16 is preferably in the bottom wall of the chamber 68, and the mechanism compartment has an opening, preferably in the rear wall of the cabinet through which air may be drawn into the chamber 72, and around the compressor and expelled thence through the condenser and the opening 74. The apparatus carried on the panel 64 may be introduced in the mechanism compartment through said rear wall opening.

The compressor 11 may be of any suitable or convenient form, although I prefer to utilize a compressor powered by means of an electric motor 25, the motor and compressor parts being enclosed in an hermetic casing to form a sealed unit having a refrigerant inlet connected by means of the conduit 21 with the evaporator and a compressed refrigerant outlet connected with the condenser, a suitable medium for lubricating the operating parts of the motor compressor unit being contained within the sealed casing of the unit. A suitable motor compressor device is shown in my co-pending application, Serial No. 724,894, filed May 10, 1934.

The condenser 13 also may be of any suitable or preferred construction, preferably comprising a series of pipe coils formed with heat dissipating fins and arranged in a casing through which a cooling medium may be circulated past the pipe coils and fins for the purpose of absorbing heat from the condenser and the refrigerating medium passing therethrough. I prefer also to provide a suitable blower, preferably a fan, powered by an electric motor 27 by means of which air or other cooling fluid may be forced through the condenser for the purpose of cooling the same.

As heretofore mentioned, the refrigeration system of my present invention is particularly well adapted for use in domestic refrigerators, for which reason I prefer to provide means for operating the compressor driving and condenser cooling motor from a single phase alternating current electrical power source, since power of this character is most usually available for the operation of domestic refrigerators. It is obvious, however, that the compressor driving and condenser cooling means may be of any suitable or preferred construction, but I prefer to utilize electric motors which may be operated and controlled simultaneously from a common power source through a common control system, in order thus to avoid duplication of motor control elements.

To accomplish the foregoing, I have shown on the drawings in Figure 3 a control system for operating electric motors 25 and 27 in parallel from a common power source. Each motor comprises a plurality of like windings 29 and 31 connected in parallel, the windings 29 being connected to receive alternating current electrical power from the power source without substantial change in phase while the windings 31 receive power from the source through a phase changer 70 whereby each motor may operate as a polyphase machine. The windings of each motor are connected together at one end and to a common conductor 33. The opposite ends of the windings 29 of each motor are also connected together and to a common conductor 35, and the free ends of

the windings 31 are connected together and to a common conductor 37. The common conductor 33 is connected to a terminal 39 located within a casing 41 which houses a part of the electrical supply and control system. The terminal 39 is connected by means of a conductor 42, preferably forming a part of a cable 43 which extends from the casing 41 to a thermostat control casing 45 located adjacent the evaporator. The opposite ends of the cable 43 may be provided with detachable plug connectors 47 and 49 to facilitate the electrical connections necessary between the electrical elements in the casings 41 and 45.

The conductor 42 when the system is assembled for operation, forms a connection with one side of a switch 51, preferably located in a casing 45, which switch is opened and closed by thermostatic means 52 including the thermostat element 53, which extends in heat exchange relationship with the atmosphere adjacent the evaporator 15, so that the switch 51 may be operated in response to temperature conditions prevailing in the vicinity of the evaporator.

The thermostatic means 52 also includes mechanism manually adjustable as by means of the control knob 55 which is preferably mounted on the casing 45 in order to determine the temperature prevailing in the vicinity of the evaporator at which the switch 51 will open or close.

The switch 51 is in series with a manually operable switch 57, which also is or may be mounted on the casing 45, and which is connected by means of a conductor 59, preferably forming a part of the cable 43 to a terminal 61 in the casing 41. The terminal 61 is connected by means of a conductor, preferably forming a part of a cable 63, with means 65, preferably in the form of an electric plug of ordinary construction, adapted for removable insertion in a power outlet socket such as is usually provided in commercial or domestic power systems. The cable 63 has another conductor adapted for detachable connection in the external power delivery circuit which conductor connects with a terminal 67 within the casing 41. This terminal 67 is in turn electrically connected with one end of a solenoid 69, also located within the casing 41, the other end of which solenoid is connected with a terminal 71 within the casing 41. The terminal 71 is also connected with the common conductor 35.

When the device 65 is connected in an external circuit, power will be delivered between the terminals 61 and 67 to energize a circuit extending between said terminals and including in series the solenoid 69, the conductor 35, the windings 29 of the motors 27 and 25, the common conductor 33, the conductor 42, the switches 51 and 57 and the conductor 59. This circuit, the switches 51 and 57 being closed, will deliver electrical power to the windings 29 of both motors, which power will be substantially in phase with the power source.

The terminal 67 is also connected by means of a conductor 73 with one end of an induction coil 75, the other end of which is also connected through a condenser 11 with the conductor 73, the conductor induction coil and condenser being all housed within the casing 41. The induction coil 75 has caps connected to stationary contacts 79 and 81 between which a shiftable blade 83 is movable in response to the current flowing through the solenoid 69. The blade 83 is electrically connected with the common conductor 31, and is adapted to selectively connect the contacts 79 and 81 with said common conductor, and

thence to the windings 31 of the motors in response to varying current flow in the solenoid 69.

It will thus be seen that the motor windings 31 are included in a circuit extending from the terminal 67 through the conductor 73, the condenser-induction coil system 75—77, one or other of the contacts 79, 81, the conductor 37, the windings 31, and thence through the conductors 33 and 41, the switches 51 and 57, and the conductor 59 to the terminal 61. The reactive system comprising the induction coil 75 and condenser 77 is adapted to shift the phase of the power applied to the windings 31, so that these windings when so energized form with the windings 29, polyphase motor driving means.

The blade 83 is adapted to vary the reactive effect of the network comprising the induction coil 75 and the condenser 77. The motors preferably employed are of the so-called capacitor induction motors, the windings comprising split phase windings adapted to be energized so that the motors may be started in operation from standstill position when energized with single phase alternating current applied between the terminals 61 and 67. It will be noted that both of the parallel circuits including the windings 29 and 31 are controlled by the switches 51 and 57, so that when the plug 65 is connected to a power outlet, the motors will remain inactive until both of the switches 51 and 57 have been closed. The switch 57 being manually operable, affords manual control for the motor while the switch 51 provides for automatic control, so that the motors and hence the refrigerating system, may be placed in operation automatically whenever the temperature in the vicinity of the evaporator rises above a predetermined value, which value may be determined by means of the knob 55.

When the plug 65 is connected with an external power source, alternating current will be delivered through the parallel circuits heretofore mentioned, which includes the several windings of the motors. The current delivered to the windings 29, however, will have a different phase relationship with respect to that delivered to the windings 31 because of the reactive effect, provided by the induction coil 75 and the condenser 77. In this way a rotating field may be created in the motors for the purpose of starting the same.

At the instant of starting, the switch 83 will engage one or other of the contacts 79, 81 in order that the proper phase relationship to start the motors will prevail in the current delivered to the windings. As the motors reach normal operating speed, the current flowing in the coils 69 will decrease, and the switch 83 will be moved under the influence of the solenoid, and will engage the other of said contacts 79, 81, in order to alter the reactive effect produced upon the current flowing to the motor windings 31, and thus to provide a desired phase relationship of current flowing in the windings for maximum operating efficiency after the motors have reached normal operating speed.

The electrical system also includes a circuit 85 containing a lamp 87, and a switch 89, said circuit being connected between the conductor 59 of the cable 43, and another conductor 91 forming a part of said cable, and connected to the terminal 67, so that whenever the plug 65 is connected to the external power source, the lamp 87 will be energized providing the switch 89 is closed. The lamp 87 is or may be arranged in any suitable or convenient position within the refrigerator com-

partment, while the switch 89 is arranged to cooperate with the door giving access to the compartment. The door, when closed, is arranged to hold the switch 89 in open position, the switch closing to energize the lamp and illuminating the interior of the refrigerator compartment whenever the door is opened.

As heretofore mentioned, the motor-compressor unit, the condenser, condenser cooling motor, the float valve, the dehydrator, and the mechanism contained in the housing 41, are mounted on the panel 64 for assembly as a unit in the mechanism compartment, while the evaporator and the control mechanism, supported in and by the casing 45, which is mounted on the evaporator, may be assembled as a unit in the refrigerating compartment 58. The cable 43 and the refrigerant conduits 21 and 23 are preferably built into the insulated walls of the cabinet in position to facilitate the necessary connections with the evaporator and the apparatus within the mechanism compartment after the same have been assembled in the cabinet. This arrangement greatly simplifies the assembly of the refrigerating system in the cabinet, and thus reduces manufacturing costs.

The evaporator also is of simple and inexpensive construction, being preferably formed of sheets 97 and 99 of heat conducting material. These sheets are formed in such a way, that when fitted and secured together, passages in which the refrigerant may be evaporated are formed between the sheets. To this end the sheet 97 is formed with spaced header forming depressions 101 near the opposite end edges of the sheet, and one of the sheets is provided with a series of parallel duct-forming grooves 103 so that when the sheets are fastened together, the depressions and grooves form spaced header chambers 111 and 112 interconnected by a plurality of parallel ducts 104. The depressions 101 and 102 and the grooves 103 are preferably formed in the sheet 97 and the other sheet 99 is assembled in position to overlie the depressions 101 and grooves 103, the sheets being secured together as by curling the edge of one sheet about the edge of the other, as shown at 105, and by welding around the peripheral edges of the sheets and between the grooves 103 to form a closed refrigerant space defined, between the plates, by the header forming depressions and interconnecting grooves.

The sheet 99, also, is preferably formed with depressions 107 and 109 in position respectively opposite the depressions 101 and 102, so that the depressions 101 and 102 cooperate, in the evaporator unit, respectively, with the depressions 107 and 109 to form the elongated cylindrical header chambers 111 and 112. One of the sheets, preferably the sheet 99, is also formed at intervals with depressions or grooves 113, forming ducts 114 intersecting and communicating with the ducts 104.

After the formed sheets 97 and 99 have been secured together in substantially flat condition, they may be bent to provide a channel-shaped evaporator element having a cross-sectional configuration substantially as shown in Figure 5 of the drawings, and comprising spaced apart side walls 115 and a bottom wall 117, the side walls containing the header chambers, with the refrigerant ducts 104 extending beneath the header spaces in the side walls 115 and in the bottom wall 117. The ridges 113 project inwardly of the facing surfaces of the walls 115, and form pairs of registering ridges on and between which objects to be cooled may be supported. In Figure 75

5 of the drawings I have indicated in dotted lines an object comprising a tray 119, adapted to contain liquid to be refrigerated, mounted between the walls 115 and supported on a shelf 121, the 5 opposite edges of which rest upon and are supported by a pair of the ridges 113. The opposite ends of the sheets 97 and 99 form the upper edges of the spaced walls 115 of the evaporator unit and may be bent to form flanges 123, which may 10 be perforated as at 125 to receive supports by which the evaporator is hung or otherwise mounted within the refrigerating chamber 58.

The evaporator also is provided with an inlet connection for liquid refrigerant which is preferably positioned to deliver the refrigerant to the evaporator at a point below the header chambers. To this end I utilize one of the shelf-supporting ridges 113 to form an inlet header. The ridge, so employed as an inlet header, is provided with an opening 125 at one end, and a fitting 127 having a channel 129 is secured to the evaporator with one end of the channel in communication with the header duct 114 defined by said ridge. The fitting is provided with preferably threaded means 131 whereby the channel 129 may be connected with the conduit 23 through which liquid refrigerant is delivered from the compressor, condenser and float valve. The fitting 127 is, of course, firmly sealed on the 20 evaporator to prevent the escape of the refrigerating medium from the system at the point of entry, and I prefer to provide a pipe 133 extending within the inlet header duct 114 with one end of the pipe in communication with the channel 129 of the inlet fitting. The other end of the pipe 133 opens in the duct 114 opposite one of the refrigerant ducts 104 located substantially midway of the opposite ends of the evaporator, so that the refrigerant will enter the evaporator 25 at said centrally located duct. I prefer to position the inlet fitting at the end of the evaporator opposite the end at which the containers 119 are introduced into and removed from the shelves 121, it being understood that the evaporator is mounted in the refrigerating compartment with 30 one end facing the door to facilitate insertion and removal of objects through said door facing end. The inlet fitting also is preferably located entirely within the lateral confines of the evaporator walls in order to eliminate lateral projections. 35

The evaporator is also provided with an outlet for evaporated refrigerant which outlet is also located within the lateral confines of the evaporator walls and which preferably comprises a fitting 135 secured in an opening formed preferably in the sheet 99 at the header space 111. The fitting 135 has an extension comprising a pipe or conduit 137 extending within the chamber 111 and having an end opening above the normal liquid refrigerant level therein. The pipe 137 communicates with a channel in the fitting 135, and the fitting is formed with a preferably threaded portion 139 by means of which the channel 40 may be connected with the refrigerant conduit 21 leading to the suction side of the compressor. The outlet fitting 135 may, of course, be connected in either or both of the headers, but I prefer to connect it in the header forming portion 109, and to interconnect the header chambers by means of a conduit 141 fastened to and between the header forming portions 107 and 109, whereby gasified refrigerant collecting in the header chamber 112 may escape through the conduit 141 into the header 111 and thence, 45

5 through the outlet fitting, to the compressor. The connecting conduit 141 in addition to its gasified refrigerant conducting function, increases the strength and rigidity of the evaporator by assisting in holding the spaced walls 115 rigidly in spaced relationship. The conduit 141 also provides a convenient handle for carrying the evaporator unit and holding the same in position while it is being assembled in the cabinet. 5

10 When the evaporator is in operation in a refrigerating system, the level of the liquid refrigerant in the evaporator is normally maintained at an elevation in the headers as shown in Figure 5 of the drawings, the outlet pipe 137 opening above said level. The refrigerating medium which I prefer to use in the system, comprises dichloromethane, and I prefer to operate the system under pressure conditions such that the liquid refrigerant entering the evaporator will boil at the temperature prevailing in the vicinity of the evaporator, that is to say, within the refrigerating compartment. I prefer also to use a mineral oil for lubricating the compressor. This oil is insoluble in gaseous dichloromethane, but is soluble in the refrigerant when liquid. Even though lubricant is not soluble in dichloromethane when in gaseous condition, slight traces of the lubricant may escape from the compressor by entrainment with the compressed gaseous refrigerant discharged to the condenser. The 20 gaseous refrigerant liquefies in passing through the condenser, and the entrained lubricant will then dissolve in the refrigerant, and I have found in operation that the liquid refrigerant delivered from the condenser contains appreciable traces of dissolved lubricant which is carried in solution with the refrigerant into the evaporator. The lubricant does not, of course, evaporate at temperatures prevailing at the evaporator, and since dichloromethane and other refrigerants, which 25 may be utilized in systems embodying my invention, have the capacity of dissolving lubricant in any proportion, it will be apparent that, if no means is provided for extracting the dissolved lubricant from the evaporator, the lubricant in the system will eventually become concentrated in the evaporator and thus not only impair the lubrication of the compressor but also impair the efficiency of the evaporator. I consequently provide a lubricant separator and extractor which, 30 35 in the illustrated embodiment, is formed as an integral part of the evaporator. 40

The lubricant separator and extractor may be of any suitable or preferred construction, and I have shown an extractor comprising a strip 55 of sheet metal 143 secured to the inner surface of one of the shells forming the evaporator to form a pocket 145, the strip 143 being secured to the shell portion at its opposite ends and along its lower edge, the upper edge of the strip 60 being spaced from the shell. The strip 143 is formed with a struck-out portion 147 opposite and in position to overhang the inner end of the exhaust outlet 137.

65 During the operation of the refrigerating apparatus the liquid in the header boils violently so that a certain amount of liquid is continuously tossed upwardly within the header and a portion drops into the pocket 145. The vigorous ebullition is promoted by delivery of the liquid 70 through the tube 137 into a localized portion of the groove 113 at the end of the tube at one of the intersecting header connected grooves 103 so that the introduction of cold refrigerant into the relatively warmer liquid in the evaporator 75

promotes vigorous boiling in said duct and results in substantial spattering in the header adjacent the receiver 145. The liquid may continue to boil in the pocket thus evaporating the 5 refrigerant so that the pocket 145 becomes filled with liquid lubricant to the level of the struck-out portion 147. As additional lubricant enters the pocket with the separated liquid refrigerant, the level of the entrapped lubricant rises and 10 the excess lubricant escapes continuously out of the pocket along the lip 147, thereby draining directly into the exhaust pipe 137, whence it is carried back to the suction side of the compressor along with the gases evolved by the boiling 15 of the refrigerant in the evaporator. •

It is thought that the invention and its numerous attendant functions and advantages will be understood from the foregoing description; and it is obvious that numerous changes may 20 be made in the form, construction and arrangement of the several parts of the illustrated apparatus without departing from the spirit and scope of the invention, and without sacrificing any of its attendant advantages, the embodiment 25 herein shown being merely a preferred arrangement for the purpose of illustrating my inventive concept.

What I claim as new and desire to secure by Letters Patent of the United States is:

- 30 1. An evaporator or boiler comprising a plurality of formed sheets welded together to form an evaporator space between the sheets, at least one of the sheets being embossed to form, with another of said sheets, a header chamber in the evaporator, at least one of the sheets being embossed to form a plurality of ducts opening at their ends in the header chamber, said evaporator being adapted to receive a body of evaporable liquid to a level in said header chamber and 40 to receive the gases developed by ebullition of said liquid in said header chamber above the liquid level therein, means comprising a partition in said header defining a pocket therein on one side of said partition and opening upwardly in said header chamber above said ducts, in position to receive liquid spattered upwardly of the surface of the liquid in the header on the other side of said partition due to ebullition of the liquid in said evaporator, said partition being 45 formed to provide an overflow, and an outlet in said header disposed in position with respect to said overflow to receive liquid delivered from said pocket through said overflow into said outlet.
- 55 2. An evaporator as set forth in claim 1, wherein the overflow comprises a lip formed in the partition.
3. An evaporator as set forth in claim 1, wherein the overflow comprises a lip bent from the plane of the partition opposite said outlet.
- 60 4. An evaporator as set forth in claim 1, wherein the overflow comprises a lip bent from the plane of the partition between spaced slits formed therein.
- 65 5. An evaporator as set forth in claim 1, wherein the outlet comprises a channelled fitting in said header having an opening extending above the normal liquid level in the header and positioned beneath said overflow.
- 70 6. An evaporator or boiler comprising sheet metal means forming an evaporator space comprising a header and a duct opening into the header, said evaporator being adapted to receive an evaporable liquid therein to a desired level 75 in the header, extractor means comprising a

receiver element disposed in said header in position facing upwardly above the liquid level therein and opposite said duct, and means for delivering an evaporable liquid into said duct at a point removed from said header whereby to produce vigorous ebullition of the liquid immediately beneath the receiver element. 5

7. An evaporator or boiler comprising sheet metal means forming an evaporator space comprising a header and a duct opening into the header, said evaporator being adapted to receive an evaporable liquid therein to a desired level in the header, extractor means comprising a receiver element disposed in said header in position facing upwardly above the liquid level therein 10 and opposite said duct, means for delivering an evaporable liquid into said duct at a point removed from said header whereby to produce vigorous ebullition of the liquid immediately beneath the receiver element, a suction connection 15 on said evaporator above the liquid level in said header, and means forming a conduit for draining liquid from the receiver element to said suction connection. 20

8. An evaporator or boiler comprising sheet metal means forming an evaporator space comprising an elongated horizontally disposed header and a duct extending downwardly of and, at its upper end, opening into the header intermediate the opposed ends of the header, said evaporator being adapted to receive an evaporable liquid therein to a desired level in the header, extractor means comprising a receiver element disposed in said header in position facing upwardly above the liquid level therein and substantially opposite the upper end of said duct, and means for delivering liquid into the duct at a substantial distance below the header whereby to produce vigorous ebullition of the liquid immediately beneath said receiver element. 30

9. An evaporator or boiler comprising sheet metal means forming an evaporator space comprising spaced headers and a plurality of ducts opening at their opposite ends in the headers, said evaporator being adapted to receive an evaporable liquid therein to a predetermined level in said headers, extractor means in at least one of said headers comprising a receiver element disposed in position facing upwardly above the liquid level therein substantially opposite at least one of said ducts, and means for delivering liquid into the duct opening in said header opposite said receiver element whereby to produce vigorous ebullition of the liquid beneath said receiver element. 45

10. An evaporator or boiler comprising sheet metal means forming an evaporator space comprising spaced headers and a plurality of ducts opening at their opposite ends in the headers, said evaporator being adapted to receive an evaporable liquid therein to a predetermined level in said headers, extractor means in at least one of said headers comprising a receiver element disposed in position facing upwardly above the liquid level therein substantially opposite at least one of said ducts, and means for delivering liquid into the duct opening in said header opposite said receiver element whereby to produce vigorous ebullition of the liquid beneath said receiver element, means interconnecting said headers above the liquid level therein, a suction connection on at least one of said headers above the liquid level therein, and means for draining liquid from said receiver element into said exhaust connection. 50

11. An evaporator or boiler comprising a plurality of formed sheets secured together to form an evaporator space between the sheets, at least one of the sheets being embossed to provide a portion forming with another of said sheets a header in the evaporator, at least one of the sheets being embossed to form a plurality of ducts opening into the header, said evaporator being adapted to receive an evaporable liquid 10 therein to a desired level in the header, extractor means comprising a receiver element disposed in the header in position facing upwardly above the liquid level therein and opposite certain of said ducts, and means for delivering an evaporable liquid into the ducts at a point removed from said header whereby to produce vigorous ebullition of the liquid beneath the receiver element.

12. An evaporator or boiler comprising a pair 20 of formed sheets secured together to form an evaporator space therebetween, at least one of the sheets being embossed to provide a portion forming with the other sheet a header in the evaporator, at least one of the sheets being 25 formed to provide a plurality of ducts opening in the header, and at least one of the sheets being formed with a ridge intersecting said ducts for the purpose of interconnecting the same at points removed from the header, said evaporator 30 being adapted to receive an evaporable liquid therein to a desired level in the header, extractor means comprising a receiver element disposed in said header in position facing upwardly above

the liquid level therein and opposite said ducts, and means for delivering an evaporable liquid within said ridge and thence into said ducts whereby to produce vigorous ebullition of the liquid in the header immediately beneath the receiver element. 5

13. An evaporator or boiler comprising a pair of formed sheets secured together to form an evaporator space between the sheets, at least one of the sheets being embossed to provide a portion forming, with the other sheet, a header in the evaporator, one of the sheets being formed to provide a plurality of ducts opening in the header, the other sheet being formed with a ridge intersecting said ducts for the purpose of interconnecting the same at a point removed from the header, means forming a conduit extending in said ridge and opening therein opposite one of said ducts, said conduit having an end projecting through an opening at an end of said ridge and a liquid inlet fitting connected to the projecting end of the conduit, said evaporator being adapted to receive an evaporable liquid 20 therein to a desired level in the header, and extractor means comprising a receiver element disposed in said header in position facing upwardly above the liquid level therein and opposite the duct in which said conduit opens, whereby to produce vigorous ebullition of the liquid in the header immediately beneath the receiver element upon delivering the evaporable liquid 25 through said conduit. 30
